UNITED STATES PATENT OFFICE

170,153

FIRECRACKER CANNON

Douglas P. Davis and Duane C. Maddux,
Burbank, Calif.

Application March 26, 1953, Serial No. 24,206

Term of patent 3½ years

(Cl. D34—15)

To all whom it may concern:

Be it known that we, Douglas P. Davis and Duane C. Maddux, both citizens of the United States and residents of Burbank, California, have invented a new, original, and ornamental Design for a Firecracker Cannon, of which the following is a specification, reference being had to the accompanying drawing which forms a part hereof:

Fig. 1 is a side elevation of a firecracker cannon embodying our new design,

Fig. 2 is a top plan view taken at right angles to the axis of the barrel of the cannon,

Fig. 3 is an elevational view taken at the left hand end of Fig. 1,

Fig. 4 is an elevational view of the right hand end of Fig. 1 taken on the axial line of the barrel of the cannon, and

Fig. 5 is a bottom plan view taken at right angles to the axis of the barrel of the cannon.

We claim:

The ornamental design for a firecracker cannon, substantially as shown.

DOUGLAS P. DAVIS.
DUANE C. MADDUX.
